LIQUID DISPENSER TOWER

Herman L. Bufington, 2840 NE. 55th St.,
Fort Lauderdale, Fla. 33308

Filed Feb. 25, 1974, Ser. No. 445,243

Term of patent 14 years

Int. Cl. D15—08

U.S. Cl. D94—3 B

FIG. 1 is an isometric view of a liquid dispenser tower showing one side of my new design, the other side being identical thereto;

FIG. 2 is a front elevational view thereof on a reduced scale;

FIG. 3 is a top plan view of FIG. 2; and

FIG. 4 is a rear elevational view of FIG. 2.

I claim:

The ornamental design for a liquid dispenser tower, as shown.
